RAILWAY TRAFFIC CONTROLLING SYSTEM

Winfred T. Powell, Rochester, N. Y., assignor to
 General Railway Signal Company, Rochester,
 N. Y.

Application July 31, 1934, Serial No. 737,781

11 Claims. (Cl. 246—3)

This invention relates to traffic controlling systems for railroads and it more particularly pertains to a system for the remote control of power operated switch machines.

In a system of remote control of power operated switch machines for use in connection with terminals, interlocking plants and centralized traffic controlling systems, it is desirable that the various controls and indications required for efficient operation of a switch machine be obtained over a minimum number of line wires between the tower or control office and the remote point where the switch is located. Therefore, one object of the present invention is to provide a simple and reliable arrangement of line circuits and relays so organized that several different distinctive controlling conditions may be simultaneously transmitted in response to the energization or de-energization of the line circuits.

More specifically, this invention provides for the transmission of the controls required for a power operated switch machine over a single polarized line circuit and the provision in such circuit of an improved arrangement for requiring the movement of the control lever at the time the locking is not effective, in order to operate the switch machine in such a manner that it will not operate after a train movement over the switch until the operator shifts the control lever to its last previous effective position.

Briefly, an electric lock equivalent arrangement is provided whereby in the event that the operator shifts the switch machine control lever while the circuits have the switch machine locked against operation, it is necessary for the operator to restore the switch machine control lever into correspondence with the position of the associated switch machine control relay before control of the switch machine is obtained, regardless of whether the switch machine remains locked or becomes unlocked in the interim.

Various other characteristic features and advantages of the invention will be in part apparent and in part specifically pointed out as the description thereof progresses.

In describing the invention in detail reference will be made to the accompanying drawing, which is a diagrammatic illustration of the present invention as applied to the control of a single track switch at a remote location.

Although the traffic controlling system of the present invention may be applied to various track layouts involving conflicting and nonconflicting routes and various other conditions encountered in practice, it has been specifically illustrated as

applied to a single track switch and preferably associated with an automatic block signal system of the type, for example, as disclosed in the pending application of S. N. Wight, Ser. No. 120,423, filed July 23, 1926.

With reference to the accompanying drawing, the railroad track switch TS is illustrated as connecting the rails 3 of a main track to the rails 4 of a diverging or turn-out track. Track switch TS is operated by a power driven switch machine SM which may be of any suitable type such, for example, as disclosed in the patent to W. K. Howe, No. 1,466,903 dated September 4, 1923. This switch machine may be provided with a dual control selector to permit hand operation of the track switch such as shown, for example, in the patent to W. K. Howe, No. 1,852,576, dated April 5, 1932.

The main track adjacent track switch TS and a portion of the diverging track to the fouling point comprises a detector track circuit of the closed circuit type with the usual track battery 5 and track relay T, which detector track circuit is insulated from the rest of the track layout by the usual insulated joints.

Traffic over the track switch in an east bound direction is governed by signals 1 and 1D on the main track and on to the turn-out track respectively. Traffic over the track switch in a west bound direction is governed by signals 2 and 2D on the main track and off the turn-out track respectively.

The track switch and the switch machine are preferably provided with point detector contacts of some suitable type such, for example, as disclosed in the patent to C. S. Bushnell, No. 1,517,236, dated November 25, 1924. These point detector contacts are employed to energize a switch position repeating relay of the usual polar neutral type in accordance with the position and the locked or unlocked condition of the track switch, but since this particular feature forms no part of the present invention it has been omitted from the disclosure for the sake of simplicity.

Referring to the drawing, a retained neutral polar relay WZ of the magnetic stick type is governed from the control office over a suitable polarized line circuit including line conductor WL. This relay may be of any suitable type in which the polar contacts are operated to one extreme position or the other in response to current flow over the line circuit in a particular direction or another. The neutral contacts of this relay remain picked up as long as the relay is energized and for a short period of time

thereafter. Also the neutral contacts of this relay are not released when the current through the winding is suddenly reversed. Such operation may be obtained, for example, in the manner disclosed in the patent to F. C. Larson, No. 1,852, 5 210 issued April 5, 1932.

Resistance RS is provided for the purpose of maintaining a substantially constant current flow through the winding of relay WZ when this relay 10 is energized by one half of battery B (contact 9 picked up) and when the relay is energized with one-half of batteries B and B¹ in series (contact 9 dropped).

Signal repeating relay M is provided to repeat 15 the condition of the signals associated with the illustrated track section. This relay is energized as long as all signals are at stop and de-energized when any one of the signals is clear. Since the method of obtaining this feature forms no part 20 of the present invention and since it is well known to those skilled in the art, the operation of this relay is merely indicated by associating the relay with contacts 11, 12 and 13 of the associated signals with a dotted line to indicate 25 that the relay is energized when the signals are all at stop.

Normally energized lock relay L is provided to 30 lock the associated switch control circuit against operation whenever the track section is occupied and whenever a signal is clear. Such a condition is obtained by de-energizing relay L to open the control line circuit extending to relay WZ. As long as the track section is not occupied and all signals are at stop relay L is picked 35 up and the switch control circuit is effective for operation.

In the control office, signal control lever SGL is indicated as controlling the signals at the 40 remote point by means of signal control line conductor GL. Since this operation forms no part of the present invention it is merely indicated by a dotted line, the detailed circuits being omitted. Switch machine control lever SML in the control office is for the purpose of controlling the 45 associated switch machine, the detailed operation of which will be explained later.

To simplify the illustrations the circuits are 50 illustrated in a conventional manner with the symbol (+) indicating the positive terminal and the symbol (−) indicating the negative terminal of a suitable battery or other source of current, with the circuits to which these terminals are connected having current flowing from (+) to (−). Symbol (B+) is associated with the (+) terminal and symbol (B−) is associated with the (−) terminal of suitable batteries B and B¹ located in the control office and at the field station respectively. These batteries or other sources of current have mid-taps (CN) which are 55 connected together by common line conductor C extending between the remote locations.

In accordance with the present invention it is contemplated that the track adjacent to switch TS will in practice be provided with track circuits, way-side signals, line circuits and the like, constituting suitable approach locking for the switch. The specific details of such approach locking circuits and other cooperating circuit arrangements are immaterial to the present invention and therefore have been omitted.

It is believed that further description of the 70 present invention will best set forth the characteristic features and functions of the system by considering the operation under certain characteristic or typical conditions.

Operation

Normal conditions.—With the detector track section unoccupied and with the switch control lever SML in the position illustrated the various devices, relays and circuits assume positions and conditions of energization as illustrated. Since it is assumed that the track section is unoccupied track relay T is normally energized. Since all signals are at stop a circuit is completed for energizing relay M. With relays M and T energized a circuit is closed for energizing relay L which extends from (+), front contact 6 of relay M, front contact 7 of relay T and winding of relay L, to (−).

Relay WZ is energized over a circuit extending 15 from the (B+) terminal of battery B, lever SML in its normal position, line WL, front contact 8 of relay L, winding of relay WZ, front contact 9 of relay WZ and line conductor C, to (CN). Current over this circuit maintains the neutral contact of relay WZ picked up and positions the polar contacts to the right.

Manual control of track switch.—It will now be assumed that the operator moves lever SML to its reverse dotted line position. The contacts 25 of this lever are preferably of the snap action type so that there never will be more than a momentary interruption of current flowing in the line circuit due to the switching of these 30 contacts from one position to another.

The actuation of lever SML to its reverse position closes a circuit from the (B−) terminal of battery B, over the contact of lever SML in its reverse dotted line position and over the remainder of the previously described circuit 35 to (CN). The sudden reversal of current over this circuit does not drop contact 9 of relay WZ but the polar contacts of this relay are actuated to the left.

Polar contact 10 of relay WZ is the purpose 40 of operating the switch machine to its normal and its reverse positions in accordance with the position of relay WZ. The detailed circuits for providing this operation are not shown but are merely indicated by the dotted line connection leading from the contacts of relay WZ to the switch machine.

The operation involved in actuating the track switch from its reverse locked position to its 50 normal locked position is merely the inverse of that described and need not be specifically pointed out. It need only be mentioned that the return of lever SML to its normal position reverses the current flow through relay WZ for 55 positioning the polar contacts of this relay back to their right hand (normal) positions and that during this reversal of current through the winding of relay WZ neutral contact 9 is not dropped so that the normal circuit for the relay 60 is not interrupted.

Manual control of signals.—Assuming clear traffic conditions, either signal 1 or 2 may be cleared with the track switch in a normal position and signal 1D or 2D may be cleared with the track switch in a reverse position. The signals are governed in accordance with the position of signal lever SGL and as above mentioned the detailed circuits for clearing the signals are not shown. It will be understood that the series circuit including relay M is opened when any signal is cleared due to the opening of some 70 one of the contacts 11, 12 or 13.

The de-energization of relay M in response to clearing a signal opens the energizing circuit of 75

relay L at front contact 6 causing relay L to be de-energized. The dropping of front contact 8 of relay L locks the switch control circuits so that the operator does not have control over relay WZ during the time that a signal governing traffic over the track switch is clear. The opening of front contact 8 of relay L de-energizes relay WZ which drops neutral contact 9 and leaves the polar contacts in their last operated positions.

Electric lock equivalent.—In the event that the operator actuates lever SML to a new position while the track switch is locked, as indicated by relay L being de-energized, this actuation is ineffective to condition the control circuits. With the circuits in the conditions indicated, it will be assumed that relay L is dropped and that the operator actuates lever SML to its reverse position before relay L is picked up. It will be understood that relay L may be dropped by the clearing of a signal or by the occupancy of the track section as above described. Since the switch control line circuit WL is open at front contact 8 of relay L the actuation of lever SML is ineffective to energize relay WZ.

In the event that the switch becomes unlocked (relay L picking up) while lever SML is in its reverse position relay WZ will not be energized because the (B-) terminal of battery B is connected over the switch control line circuit and winding of relay WZ, back contact 9 of relay WZ, resistance RS and contact 14 of relay WZ to the (B-) terminal of battery B¹. It is therefore necessary for the operator to restore lever SML to its normal position before control of the WZ relay can be re-established. This closes a circuit from the (B+) terminal of battery B, lever SML in its normal position, conductor WL, front contact 8 of relay L, winding of relay WZ, back contact 9 of relay WZ, resistance RS, contact 14 of relay WZ in its right hand (normal) position, through the right hand portion of battery B¹ in a direction which aids the right hand portion of battery B and over conductor C to the (CN) tap of battery B. This picks up the neutral contacts of relay WZ and at its neutral contact 9, the winding of this relay is connected to common conductor C which so conditions the circuit that the actuation of lever SML to either position will effect the operation of relay WZ to a corresponding position.

Assuming the reverse condition, the actuation of lever SML to its normal position (with relay WZ actuated to the left) connects the (B+) terminal of battery B to the (B+) terminal of battery B¹ through contact 14 of relay WZ in its left hand dotted position. This is of course assuming that relay WZ was de-energized by the opening of front contact 8 of relay L after which contact 8 was again closed.

Under this condition it becomes necessary for the operator to position lever SML in its reverse dotted line position to energize relay WZ over a circuit extending from the (B-) terminal of battery B, lever SML in its reverse dotted line position, conductor WL, front contact 8 of relay L, winding of relay WZ, back contact 9 of relay WZ, resistance RS, contact 14 of relay WZ in its left hand dotted position, (B+) terminal of battery B¹, through the left hand portion of battery B¹ and over conductor C to the (CN) tap of battery B. This will energize relay WZ and close its front contact 9, after which the polar contacts of this relay can be actuated to normal and reverse positions in response to the

operation of lever SML to corresponding positions.

It is to be understood that although only one specific embodiment of the present invention has been disclosed the principles of the invention may be applied to various other types of systems and that various types of track lay-outs may be controlled in a similar manner without departing from the spirit of the present invention. The present disclosure has been chosen merely for providing a simplified showing which could be clearly described in the specification.

Having described a traffic controlling system for one specific embodiment of the present invention, it is desired to be understood that the form is selected to facilitate in the disclosure rather than to limit the number of forms which it may assume and it is to be further understood that various modifications, adaptations and alterations may be applied to the specific form shown in order to meet the requirements of practice, all without in any manner departing from the spirit or scope of the present invention except as limited by the appended claims.

Having described my invention, what I claim is:—

1. In a centralized traffic controlling system for railroads, a track section, a track switch associated with said section, a control lever, a retained neutral polar switch control relay having its winding connected in series with its neutral contacts, means responsive to the actuation of said lever for controlling the operation of said relay, a first locking means responsive to specific conditions of said section, a second locking means including neutral contacts of said relay, means controlled by said first locking means for preventing the control of said relay by said lever, means controlled by said second locking means for allowing the control of said relay by said lever only providing the polar contacts of said relay and said lever are in correspondence, and means controlled by said relay for governing the operation of said track switch.

2. In a centralized traffic controlling system for railroads, a track section, a track switch associated with said section, a switch control relay for controlling said track switch, a control circuit, a first and a second source of current, a first control means including control lever contacts for distinctively connecting said first source of current to said control circuit, means responsive to the distinctive connection of said first source to said control circuit for distinctively controlling said switch control relay, a second control means controlled by said switch control relay for distinctively connecting said second source of current to said control circuit, a lock relay, means controlled by said lock relay for preventing the energization of said control circuit from either of said sources, and circuit means including said first and said second control means in noncorresponding positions for preventing the energization of said control circuit from either of said sources.

3. In a centralized traffic controlling system for railroads, a track section, a track switch associated with said section, a switch control relay for controlling said track switch, a control circuit, a first source of current and a second source of current, a first control means including control lever contacts for distinctively connecting said first source of current to said control circuit, means responsive to the distinctive connection of said first source to said control circuit for distinctively

controlling said switch control relay, a second means controlled by said switch control relay for distinctively connecting said second control source of current to said control circuit, a lock relay, means controlled by said lock relay for preventing the energization of said control circuit from either of said sources, circuit means including said first and said second control means in noncorresponding positions for preventing the energization of said control circuit from either of said sources, and means responsive to the energization of said control circuit for governing said track switch.

4. In a centralized traffic controlling system for railroads, a track section, a track switch associated with said section, a switch control relay for controlling said track switch, a control circuit, a first source of current and a second source of current, a first control means including control lever contacts for distinctively connecting said first source of current to said control circuit, means responsive to the distinctive connection of said first source to said control circuit for distinctively controlling said switch control relay, a second control means controlled by said switch control relay for distinctively connecting said second source of current to said control circuit, a lock relay, means controlled by said lock relay for preventing the energization of said control circuit from either of said sources, circuit means including said first and said second control means in non-corresponding positions for preventing the energization of said control circuit from either of said sources irrespective of the position of said lock relay, and means responsive to the energization of said control circuit for governing said track switch.

5. In a centralized traffic controlling system for railroads, a track section, a track switch associated with said section, a switch control relay for controlling said track switch, a control circuit, a first source of current and a second source of current, a first control means including control lever contacts for variably connecting said first source of current to said control circuit, means responsive to the variable connection of said first source to said control circuit for variably controlling said switch control relay, a second control means controlled by said switch control relay for variably connecting said second source of current to said control circuit, a lock relay, means controlled by said lock relay for preventing the energization of said control circuit from either of said sources, circuit means including said first and said second control means in non-corresponding positions for connecting said sources of current in opposing relation to said control circuit, and circuit means including said first and said second control means in corresponding positions for connecting said sources of current in aiding relation to said control circuit.

6. In a centralized traffic controlling system for railroads, a track section, a track switch associated with said section, a switch control relay for controlling said track switch, a control circuit, a first source of current and a second source of current, a first control means including control lever contacts for variably connecting said first source of current to said control circuit, means responsive to the variable connection of said first source to said control circuit for variably controlling said switch control relay, a second control means controlled by said switch control relay for variably connecting said second source of current to said control circuit, a lock relay, means

controlled by said lock relay for preventing the energization of said control circuit from either of said sources, circuit means including said first and said second control means in noncorresponding positions for connecting said sources of current in opposing relation to said control circuit, circuit means including said first and said second means in corresponding positions for connecting said sources of current in aiding relation to said control circuit, whereby said opposing or said aiding connections prevent or permit respectively the control of said switch control relay by said lever.

7. In a centralized traffic controlling system for railroads, a track section, a track switch associated with said section, a switch control relay for controlling said track switch, a control circuit, a first and a second source of current, a first control means including control lever contacts for distinctively connecting said first source of current to said control circuit, means responsive to the distinctive connection of said first source to said control circuit for distinctively controlling said switch control relay, a second control means controlled by said switch control relay for distinctively connecting said second source of current to said control circuit, a lock relay, means controlled by said lock relay for preventing the energization of said control circuit from either of said sources, and circuit means including said first and said second control means for preventing the energization of said control circuit from either of said sources.

8. In a centralized traffic controlling system for railroads; a power operated track switch; a retained neutral polar control relay for controlling the power operation of said track switch; a lock relay for at times locking said track switch; a switch control lever; a source of energy associated with said control lever; a line circuit connecting said lever and said control relay, said circuit having one polarity or the other applied thereto from said source depending upon the position of said lever, and said circuit including a contact of said lock relay and a front neutral contact of said control relay, whereby operation of said lever causes operation of the polar contacts of said control relay only while the contact of said lock relay is closed and only while said control relay neutral contacts are picked up; and circuit means including a back neutral contact and a polar contact of said control relay for picking up the neutral contacts of said control relay only when the polarity applied to said line circuit corresponds to the polar position of the polar contacts of said control relay; whereby control of the operation of said switch by said lever requires correspondence between said lever and said control relay following each closure of said line circuit by said lock relay after an opening of the line circuit.

9. In a centralized traffic controlling system for railroads; a power operated track switch; a retained neutral polar control relay for controlling the power operation of said track switch; a lock relay for at times locking said track switch; a switch control lever; a source of energy associated with said control lever; a line circuit connecting said lever and said control relay, said circuit having one polarity or the other applied thereto from said source depending upon the position of said lever, and said circuit including a contact of said lock relay and a front neutral contact of said control relay, whereby operation of said lever causes operation of the polar contacts of said control relay only while the con-

tact of said lock relay is closed and only while said control relay neutral contacts are picked up; a source of energy at said control relay; and circuit means including a back neutral contact and a polar contact of said control relay for connecting said source of energy at said control relay in series with said control relay with one polarity or the other depending on the position of said polar contact, and so as to allow current flow in said line circuit only when said control lever and said polar contacts of said control relay are in corresponding positions; whereby operation of said switch requires correspondence between said lever and said control relay following each closure of said line circuit by said lock relay after an opening of the line circuit.

10 10. In a centralized traffic controlling system for railroads, a track section, a track switch associated with said section, a control lever, a control relay having neutral and polar contacts, a single control circuit including said neutral contacts in one position distinctively energized in accordance with the position of said lever for distinctly controlling said polar contacts, means controlled by a first polar contact of said relay for governing the operation of said track switch, and means controlled by said neutral contacts in

another position and a second polar contact of said relay for permitting or preventing the control of said relay by said lever in accordance with the correspondence or noncorrespondence respectively between said lever and said second polar contact. 5

15 11. In a centralized traffic controlling system for railroads; a track section; a track switch associated with said section; a control lever; a control relay having neutral and polar contacts; a source of energy; a single control line circuit including the winding of said control relay and its neutral contacts in one position distinctively energized in accordance with the position of said lever, whereby the polar contacts of 15 said control relay are distinctively controlled; means controlled by a first polar contact of said control relay for governing the operation of said track switch; and means controlled by said neutral contacts in another position and a second 20 polar contact of said control relay for permitting or preventing the control of said control relay by said lever in accordance with the correspondence or non-correspondence respectively between said lever and said second polar contact. 25

WINFRED T. POWELL.
